UNITED STATES PATENT OFFICE.

LEON W. ROSENTHAL, OF NEW YORK, N. Y., ASSIGNEE, BY MESNE ASSIGNMENTS, TO
AMERICAN BOSCH MAGNETO CORPORATION, OF NEW YORK, N. Y., A CORPORATION
OF NEW YORK.

MAGNETO FOR IRREGULAR IGNITION.

1,341,282.

Specification of Letters Patent. Patented May 25, 1920.

Application filed October 2, 1918. Serial No. 256,505.

To all whom it may concern:

Be it known that I, LEON W. ROSENTHAL, a citizen of the United States, residing at 106 Central Park West, New York City, in the county of New York, State of New York, have invented certain new and useful Improvements in Magneton for Irregular Ignition; and I do hereby declare the following to be a full, clear, and exact description of the invention, such as will enable others skilled in the art to which it appertains to make and use the same.

The present invention relates to magnetos of the sleeve type for igniting combustible mixtures in internal combustion engines at irregular intervals, that is at unequal angles of rotation.

Air plane engines are now made with 8 to 18 cylinders in V or "fan" arrangement with the two or three planes of cylinders spaced apart differently than the usual angle, which in the case of two planes is 90° for 8 cylinders, 60° for 12 cylinders, or in general, is equal to 360° or 720° divided by the number of cylinders. Other airplane engines have their cylinders arranged in one or two circular series. In some of such engines, the departure from the usual spacing necessitates ignition at irregular intervals; for instance, an engine at present in use has 12 cylinders arranged in two planes on a 45° V and requires ignition at 75°, 45°, 75°, 45°, and so on, inasmuch as the explosions occur in cylinders of the two planes alternately.

Furthermore, the large number of cylinders, or the high speed of rotation of the engine, or both, necessitate such excessively rapid sparking that when a magneto is used it should produce more than the two sparks per rotation given by an ordinary bipolar magneto, because the speed of the magneto would otherwise be too high.

The primary object of my invention is to provide a magneto which meets the foregoing requirements, and is, therefore, intended for association with an internal combustion engine of the V, "fan", "circular" or other type having many cylinders, or rotating at high speed, or both, wherein the power strokes occur at irregular intervals, and ordinarily at recurring irregular intervals, that is at angles of rotation which are

successively unequal but alternately equal. In accordance with the invention, the armature is fixed in a position displaced from its neutral position, that is in a position displaced from the position at which the armature poles are symmetrically disposed in the field interpolar spaces, so that, in that displaced position, the trailing tips of the armature poles are separated by unequal angles from the trailing tips of the field poles. By making these unequal angles substantially the same as the irregular intervals of ignition, the magnetic flux flowing from the field magnet through the generating winding mounted on the armature or otherwise, as desired, is then altered by the magnetic members of the sleeve; and by simultaneously altering the circuit of the generating winding by suitable means such as the mechanical interrupter on an electromagnetic spark plug, ignition currents are produced at the irregular intervals and may be distributed to the spark plugs in the cylinders of the engine by a distributor having suitably arranged contacts connected to the electrodes thereof. Preferably, the armature poles partly overlap the field poles and the spans of the poles and the magnetic members of the sleeve are of such relative extent that the reversal of the flux through the armature is completed in a comparatively small angle of rotation.

I have discovered that, notwithstanding the displacement of the armature from its neutral position, and the overlap of the field and armature poles, the successive ignition voltages generated upon rotation of the sleeve are substantially alike from a low starting speed to a high running speed in either direction of rotation, and that the magnetic strength of the field magnet is not affected thereby and does not weaken more than ordinarily.

In the accompanying drawings, illustrating my invention in application, as an example, to a high tension magneto having a bipolar field and armature and a sleeve for firing a 12-cylinder 4-cycle engine with its cylinders on a 45° V,

Figure 1 represents a longitudinal cross section of the preferred embodiment of magneto; Fig. 2 is a transverse section thereof; Fig. 3 is a wiring diagram show-

ing the mechanical interrupter and the distributor associated with the magneto; and Figs. 4 to 7 illustrate the position of the rotatable sleeve at the four successive ignition periods.

The magnetic circuit of the magneto includes a stationary permanent magnet 1 with symmetrical poles 2 and an armature with symmetrical poles 3 connected by the cross bar 4. The armature is displaced from its neutral position by an angle equal to half the difference between the adjacent irregular intervals, in this case by 22.5° , so that the trailing tips of the armature poles are separated from the trailing tips of the field poles by angles of 67.5° and 112.5° . In general, the angular separation of the trailing tips of the armature and field poles is substantially equal to the irregular intervals of firing of the engine, multiplied by the ratio of the magneto speed to the engine crank shaft speed, or, in this case, to 45° times $1\frac{1}{2}$, and 75° times $1\frac{1}{2}$, respectively.

The magnetic sleeve has two iron members 5 magnetically separated from each other and held in position by the brass end plates 6, 7. These members have a like span of about 95° and are arranged to simultaneously bridge the field interpolar spaces and to later simultaneously bridge the armature interpolar spaces, each of which is substantially 90° in angular extent.

The shafts 8, 9 of the sleeve are supported in ball bearings 10, 11, carried by the supporting members 12, 13 which are secured to the base plate of a magneto. The shafts 14, 15 of the armature are mounted in ball bearings 16, 17 carried in enlarged recesses of the two shafts of the sleeve. The shaft 14 extends through and beyond the hollow shaft 8 and carries a collar 18 fast with it and with a stationary member 19 to secure the armature against rotation.

The magnetic sleeve is rotated in its bearings by the gear 20, which is of proper size to be driven from the crank shaft of the engine at the required speed ratio. As shown diagrammatically in Fig. 3, one terminal of the primary turns 21 of the generating winding is connected to one terminal of the secondary turns 22 of the generating winding and thence to the stationary insulated element 23 of the mechanical interrupter. The other terminal of the primary turns is grounded, while the other terminal of the secondary turns is connected to the rotatable brush 24 of the distributor, which is driven by the gears 25, 26, at the required speed of rotation, in this case at one-third the speed of the sleeve.

The cam member of the mechanical interrupter is fast with the sleeve and has four cams 27 spaced apart 67.5° , 112.5° , 67.5° , and 112.5° to deflect the grounded, movable element 28 of the mechanical interrupter

and thereby interrupt the primary turns of the generating winding at the irregular intervals of ignition. At those intervals, the distributor brush 24 engages the spark plug distributing contacts 29, which are correspondingly irregularly spaced to conduct the ignition currents from the generating winding to the insulated terminals of the spark plugs 30 in the engine cylinders.

The position of the sleeve members at the four irregular intervals of ignition is illustrated diagrammatically in Figs. 4 to 7. In Fig. 4, the trailing tips of the members 5 of the sleeve are leaving the trailing tips of the armature poles 3, thereby substantially interrupting the magnetic flux flowing through the cross bar 4 and therefore in the generating winding mounted thereon. Almost directly after that moment the magnetic flux is established through the armature in the opposite direction, the flux thus being reversed through the armature in a small angle of rotation of the sleeve. At 67.5° later in the rotation, the trailing tips of the sleeve members 5 leave the trailing tips of the field poles 2, as shown in Fig. 5, and almost directly after that moment, the magnetic flux is established in the opposite direction through the armature. At 112.5° after the second period of ignition, or 180° after the first, the trailing tips of the sleeve members 5 again leave the trailing tips of the armature poles 2, as shown in Fig. 6; and at 67.5° later, or 180° from the second period of ignition, those tips leave the trailing tips of the field poles, as shown in Fig. 7. At each of these ignition periods, viz., at 0° , 67.5° , 180° and 247.5° from the position of the sleeve shown in Fig. 4, the mechanical interrupter opens the circuit of the primary turns and the distributor brush engages a spark plug distributing contact to conduct to the spark plug connected thereto the ignition current then produced in the generating winding.

Having thus described my invention what I claim is:—

1. In a magneto for ignition at irregular intervals, a field magnet having poles, an armature having poles partly overlapping the field poles, a magnetic sleeve rotatable in the air gap between the field and armature poles, a generating winding, and means for altering the circuit of the generating winding at the irregular intervals determined by the trailing tips of the field and armature poles.

2. In a magneto for ignition at recurring irregular intervals, a field magnet having poles, an armature having poles overlapping the field poles by half the angular difference between the adjacent ones of said intervals, a magnetic sleeve rotatable in the air gap between the field and armature poles, a generating winding, and means for alter-

ing the circuit of the generating winding at the irregular intervals determined by the trailing tips of the field and armature poles.

3. In a magneto for ignition at irregular intervals, a field magnet having poles, an armature having symmetrical poles with each of its trailing tips disposed at unequal angles from the adjacent trailing tips of the field poles, a magnetic sleeve rotatable in the air gap between the field and armature poles, a generating winding, and means for altering the circuit of the generating winding at the irregular intervals determined by the trailing tips of the field and armature poles.

4. In a magneto for ignition at recurring irregular intervals, a field magnet having symmetrical poles, an armature having symmetrical poles with each of its trailing tips disposed at unequal angles from the adjacent trailing tips of the field poles, a generating winding, and means for altering the circuit of the generating winding at the recurring irregular intervals determined by the trailing tips of the field and armature poles.

5. In a magneto for ignition at irregular intervals, a field magnet having poles, an armature having symmetrical poles displaced from their neutral position, the angular separation of the trailing tips of the field and armature poles being substantially equal to the irregular intervals, a generating winding, a magnetic sleeve rotatable in the air gap between the field and armature poles to alter the magnetic flux in the generating winding at the irregular intervals, and means for altering the circuit of the generating winding substantially at said intervals.

6. In a magneto for ignition at irregular intervals, a field magnet having symmetrical poles, an armature having symmetrical poles displaced from their neutral position, the angular separation of the trailing tips of the field and armature poles being substantially equal to the irregular intervals, a generating winding, a magnetic sleeve rotatable in the air gap between the field and armature poles to alter the magnetic flux in the generating winding at the irregular intervals, and means for altering the circuit of the gen-

erating winding substantially at said intervals.

7. In a magneto for ignition at irregular intervals, a field magnet having poles, an armature having poles, the trailing tips of the field and armature poles being angularly separated by the irregular intervals, a generating winding, a magnetic sleeve rotatable in the air gap between the field and armature poles and having magnetically-separated magnetic members, each field interpolar space and each armature interpolar space being substantially equal to the span of a member of the sleeve, and means for altering the circuit of the generating winding substantially at said intervals.

8. In a magneto for ignition at recurring irregular intervals, a field magnet having symmetrical poles, an armature having symmetrical poles partly overlapping the field poles, a sleeve having like magnetic members magnetically-separated from each other and rotatable in the air gap between the field and armature poles, the span of the field and armature poles being alike and equal to that of said members and also equal to that of the field and armature interpolar spaces, a generating winding, and means for altering the circuit of the generating winding at recurring irregular intervals determined by the trailing tips of the field and armature poles.

9. In a magneto for ignition at recurring irregular intervals, a bipolar field magnet having poles of substantially 90° span, a bipolar armature having poles of substantially 90° span and partly overlapping the field poles, a generating winding on the armature, a magnetic sleeve rotatable in the air gap between the field and armature poles and having two magnetically-separated magnetic members of substantially 90° span arranged to reverse the magnetic flux in the generating winding during periods angularly separated by the irregular intervals, and means for altering the circuit of the generating winding at said intervals.

In testimony whereof I affix my signature.

LEON W. ROSENTHAL
